UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed May 20, 1921. Serial No. 471,173.

To all whom it may concern:

Be it known that I, BURNHAM C. STICKNEY, a citizen of the United States, residing in Elizabeth, in the county of Union and 5 State of New Jersey, have invented certain new and useful Improvements in Typewriting Machines, of which the following is a specification.

This invention relates to sound-deadening hoods or casings for typewriting machines, and is of the same general type disclosed in my co-pending application, Serial No. 429, 10 617, filed December 10, 1920 (now Patent No. 1,519,224, dated December 16, 1924).

15 The invention comprises, in combination with a typewriting machine, a sound-deadening casing or hood for enclosing the noise-producing parts of the typewriting machine, while the keys and other parts of the 20 machine used in its operation, which are suitably arranged for the purpose, project through the hood.

The invention provides for a longitudinal slot at the front between a lower body or 25 part and an upper, rearwardly-swingable, hinged cover, dome or part, beneath which a plurality of carriage-controlling finger-pieces may project, said finger-pieces working in said slot. The carriage in the present 30 invention may be mounted to travel within the cover part between the end walls thereof.

It is one feature of this invention to provide a sound-muffling means, in addition to the sound-deadening hood, by closing the 35 passages in the frame of the typewriting machine through which sound was hitherto able to issue freely from the machine to the casing.

Another feature of this invention is the 40 provision of means for transmitting the sound of the line-end bell-signal to the exterior of the sound-deadening casing. The bell-signal is ordinarily mounted on the frame of the typewriting machine and consequently within the casing, but in the present 45 invention the bell is extended laterally to project through the sound-deadening casing, the parts co-operating with the bell-signal being suitably modified.

50 Another feature of this invention is the provision of means whereby the platen may be rotated as freely in either direction from the exterior of the hood as by the ordinary finger-wheels or knobs, and for this purpose

a shaft having a finger-wheel at its forward 55 end projects through the front slot in the casing and is connected at its other end to the platen shaft or axle to rotate the shaft when the finger-wheel is operated.

Still another feature of this invention is 60 the provision of improved means for attaching a removable front cover-plate for the lower body part of the sound-deadening hood, which enables the hood to be more readily applied to the machine, and which 65 enables the lower body part to be readily assembled.

Other features and advantages will hereinafter appear.

In the accompanying drawings, 70

Figure 1 is a front elevation of the sound-deadening hood applied to an Underwood standard typewriting machine as modified by the invention.

Figure 2 is a plan view of the device 75 shown in Figure 1, the cover part of the hood having been removed to expose the interior.

Figure 3 is a detail showing the bell-signal 80 as applied to the machine in the present invention.

Figure 4 is a vertical section of the hood taken on the line 4-4 of Figure 1.

The Underwood standard typewriting machine comprises a main frame 10 and a 85 forward extension 11 of said frame, within which extension are positioned banks of keys 12 fixed to the ends of key-levers 13, which operate bell-cranks 14 to swing type-bars 15 upwardly and rearwardly to strike 90 against the platen 16. Said platen is fixed upon a shaft 17 journaled in the end walls 18 of a platen frame 19 forming part of the usual carriage 20, which rides on a front rail (not shown), and a rear rail 21. The 95 platen may be rotated within the hood by a finger-wheel or knob 22 fixed to one end of the shaft 17, and may be line-spaced from the outside of the hood by a handle 25 (of a form to be described hereinafter) operating the usual line-space mechanism comprising a slide 26. The platen may be rotated in either direction by additional means projecting outside the hood, said means comprising a finger-wheel 30 at the 105 end of a forwardly-projecting rod 31 having a universal joint 32 at a point intermediate its length to allow for case-shifting

of the platen, and having a gear 33 at its end meshing with a similar gear 34 fixed on the end of the platen shaft 17. The gear 34 is staked to shaft 17, which is journaled in 5 one end of a supporting bracket 35, the other end of which is fixed to the wall 18 of the platen frame 19, and the gear 33 is staked to the rearward portion of rod 31, which is journaled in a hub 37 at one end of a substantially right-angled bracket 38 having a hub 39 in which the shaft 17 is journaled, 10 the bracket 38 being so proportioned that the gears 33 and 34 will be held in meshing engagement. When the platen is shifted, the shaft 17, the bracket 38, and hence gears 15 33 and 34 and the rearward portion of rod 31 will move as a unit, the universal joint 32 permitting the rearward portion of rod 31 to move relatively to the forward portion, which is held to the non-shifting carriage frame by a bracket 40 fixed at one end to the carriage frame and having a hub 41 at the other end in which the forward portion of rod 31 is journaled. The carriage is 20 provided with the usual carriage-release-lever 42 which has a forward extension 43, a carriage-return finger-piece 44 fixed to said carriage, and the usual pointer 45 co-operating with a scale 46 on the main frame of the machine, the form of said lever 42 and finger-piece 44 being described more fully 25 hereinafter.

The typewriting machine rests upon a sound-deadening base-plate or pad 50, which 30 forms the bottom plate for the sound-deadening casing or hood, the latter comprising a lower, body portion 51 and an upper or cover portion 52. The body portion comprises a front wall 53, end walls 54, and a rear wall 55, the front wall being provided 35 with an opening large enough to receive the main typewriter frame 10. The body portion has extensions 56 forming a container at either side in which the carriage travels to the right and left. The cover portion 52 is hingedly connected by a rear wall 57 to the rear wall 55 at 58, and comprises side walls which co-operate with the outer limits 40 of the extensions 56 of the body part, a forwardly-extending and downwardly-sloping top wall 60, which may be a continuation of the rear wall 57, and a short front wall 61 terminating some distance below the top of the carriage and considerably above the top 45 edge of the front wall 53 of the body part. The top wall 60 is provided with transparent plates 62 supported in any well known manner, as by bars 63 forming grooves for receiving the plates and facilitating replacement, said plates occupying substantially the 50 entire top wall, thus rendering visible the typing of work-sheets around the platen. The plates 62 are spaced from each other in order to prevent more effectually the transmission of sound therethrough, and are held 55

in place by suitable clamps 59. The various parts of the body part and cover part of the casing heretofore described are held together and re-enforced in any well known manner, 60 as by angle-irons 64.

It will be apparent that the front wall 53 of the body part terminates at its top a distance below the carriage to permit the typewriter to slide into the hood from the front. The front wall 61 of the cover part terminates about midway of the platen, thus leaving a large opening in the front of the hood. To partially close this opening, there is provided a releasable front cover-plate 70 shaped like the front wall 53 but extending 65 upwardly a greater distance, said cover-plate being mounted, by large openings or key-hole-slots 72 on studs 71 passing through the front wall 53 and lodging in the angle-irons 64. The cover-plate is then lowered, 70 the studs passing upwardly in extensions of said openings which are narrowed sufficiently to prevent the cover-plate from sliding off the heads of the studs. The cover-plate is then fixed by means of screws 74 75 passing into the front wall and the angle-irons 64. It will thus be seen that, by merely removing screws 74 and lifting plate 70 upwardly to bring the large openings 72 opposite the studs, the cover-plate may be 80 readily removed.

The upper edge 75 of the front cover-plate does not reach the lower edge 76 of the front wall 53, thus leaving a slot 80, which is 85 closed to prevent the escape of sound, there being provided for this purpose upper and lower slot-closing cushion strips 81 and 82, which may be formed of a loop or fold of suitable material, such as plush, felt or soft leather. The upwardly-extending two-ply margin of the upper cushion strip 81 is secured upon the inner side of the front wall 61 adjacent the lower edge thereof, and the lower cushion strip is similarly secured upon the inner side of cover-plate 70 adjacent the 90 upper edge thereof by means of clamping strips 83 held in place by any suitable means such as screws or rivets. The cushion strips 81 and 82 meet on a line slightly below the level of the platen axis. It is desirable to 95 operate the machine, that is, to line-space the platen, return the carriage to the right, release the carriage from the rack, and rotate the platen, whenever desired, without lifting the cover of the hood. Since the line-space handle 25, carriage-return finger-piece 44 and carriage-release-lever extension 43 are mounted on a level with the front bar 47 of the carriage, it is necessary to curve these members downwardly, as well as extend them forwardly to project through slot 80. The finger-wheel 30 for rotating the platen projects through the slot on the forward portion of rod 31 in a manner similar to the levers and finger-pieces mentioned above. 100

It has been found that a substantial portion of the noise produced by the operation of a typewriting machine can be eliminated by muffling means before the sound passes outside the main frame 10. For this purpose, sound-deadening material is provided to close the open side, front, and rear walls, and the bottom of the spaces between the feet of the machine as well as the space beneath the key-levers. The bottom of the frame is closed by a strip 90 of felt or other sound-deadening material resting on the base 50, and of a thickness to fill the space between the base 50 and the bottom of the frame 10, said space being due to the frame supports or feet 91. The strip occupies the substantially rectangular space between the feet 91. The front of the main frame is partially open, beneath the guide plate or comb 92 in which operate the key-levers, and to close this space a layer 93 of sound-deadening material is provided between the front feet 91, said layer extending upwardly from the pad 50 and terminating a short distance below the key-levers to allow free downward movement of the latter. A similar layer 94 is provided for closing the entire rear opening of the machine frame, and a strip 88 closes the space between the rear feet 91. The openings 89 in the sides of the frame may be closed by layers 95. The noise of operation of the key-levers can be deadened to a large extent by placing a layer 96 of sound-deadening material on the key-levers between the points of connection with the bell-cranks and the front wall, and another layer 97 to the rear of said points and extending to the rear of the frame. These layers 96 and 97 of felt also further prevent the sound of the striking type-bars from emanating beneath the key-levers. The above-described sound-insulation will deaden much of the sound before leaving the typewriter frame, the rest of the sound being readily absorbed by the hood. The various pads or sheets of sound-deadening material co-operate with the typewriter framework to form air-pockets within the frame; and the hood forms an air pocket or pockets outside of the frame.

The bell-signal, which gives a warning at the end of a line, would not be heard if contained within the hood. The bell-signal is therefore mounted so as to project to the exterior of the hood, and for this purpose a rod 100 threaded at one end in the bracket 102 on the machine projects outwardly to the side wall of the casing and carries the bell 101 at its other end. After the hood has been applied to the machine, the bell may be assembled on rod 100 and fixed in position, in a hole in the side wall of the hood, by nut 103 engaging the opposite end of the rod. The bracket 102 is

the one ordinarily used for the usual bell-mounting. The bell hammer 104, which ordinarily projects directly rearwardly, has a bent portion 105 projecting laterally from the bell-operating lever 106 pivoted on the machine. The bell-signal will thus be operated in the usual manner and will emit a full sound.

It will be understood that the cover and the body portion of the casing may be lined with any suitable sound-deadening material, such as felt.

The following claims are limited to inventive organizations that are not disclosed in my co-pending application, No. 381,259, filed May 14, 1920.

Variations may be resorted to within the scope of the invention, and portions of the improvements may be used without others.

Having thus described my invention, I claim:

1. The combination with a typewriting machine comprising a traveling carriage having a platen-frame mounted therein, and a platen-journalized in said platen-frame, of a sound-deadening casing for the machine, said casing comprising a lower body part and an upper cover part hinged at the rear to said body part, there being a slot at the front between said body part and said cover part, and means connected to said platen and projecting forwardly through said slot whereby said platen may be rotated from the front of the casing, said means operating in said slot when said carriage travels to the right or left, and being provided with a finger-wheel outside of said casing for rotating said platen in both directions.

2. The combination with a typewriting machine comprising a platen, a shaft upon which said platen is fixed, and a traveling carriage in which said shaft is mounted, of a sound-deadening casing for the machine having at its front a slot extending in the direction of carriage-travel, and means connected to said platen and projecting forwardly through said slot for rotating said platen from the front of the casing, said means being connected with the carriage to travel therewith, and comprising an operating shaft projecting through said slot, a gear fixed to the rearward end of said operating shaft, and a gear fixed to one end of the platen-shaft and meshing with said first gear.

3. The combination with a typewriting machine comprising a case-shift platen-frame, a shaft journalized in said frame, a platen fixed to said shaft, and a traveling carriage in which said platen-frame is shiftable, of a sound-deadening casing for the machine having a slot extending in the direction of carriage-travel, and carriage-supported means connected to said platen and projecting forwardly through said slot

for rotating said platen from the front of the casing, said means comprising an operating shaft extending through said slot, a gear fixed to the rearward end of said operating shaft, a gear fixed to one end of the platen-shaft and meshing with said first gear, and a bracket fixed to said platen-frame and supporting said shafts to hold said gears in meshing engagement in the lowered and 10 shifted positions of said platen.

4. The combination with a typewriting machine comprising a platen-frame, a shaft journaled in said frame and a platen fixed to said shaft, of a sound-deadening casing 15 for the machine, means connected to said platen and projecting forwardly through said casing whereby said platen may be rotated from the front of the casing, said means comprising an operating shaft having 20 a forward part and a rearward part, a universal joint connecting said parts, and a gear fixed to the rearward end of said rearward part, a gear fixed to one end of the platen shaft and meshing with said first 25 gear, and a bracket fixed to said platen-frame and supporting said platen shaft and the rearward part of said operating shaft, to hold said gears in meshing engagement in the lowered and shifted positions of said 30 platen, said universal joint permitting said rearward part of the operating shaft to move relatively to said forward part when the platen is shifted.

5. The combination with a typewriting machine comprising a carriage in which is 35 mounted a platen-frame, a shaft journaled in said frame and a platen fixed to said shaft, of a sound-deadening casing for the machine, means connected to said platen and projecting forwardly through said casing whereby said platen may be rotated from the front of the casing, said means comprising an operating shaft having a forward part and a rearward part, a universal joint 40 connecting said parts, and a gear fixed to the rearward end of said rearward part, a gear fixed to one end of the platen shaft and meshing with said first gear, a bracket fixed to said platen-frame and supporting said 45 platen shaft and the rearward part of said operating shaft, to hold said gears in meshing engagement in the lowered and shifted positions of said platen, said universal joint permitting said rearward part of the operating shaft to move relatively to said forward part when the platen is shifted, and a bracket fixed to said carriage and supporting the forward part of said operating shaft.

6. The combination with a typewriting machine having an open frame with an open 60 base and feet to space said frame from a support on which the feet rest, of sound-deadening means for said machine, including pads of sound-deadening material closing the sides and back of said frame, and

a pad of sound-deadening material resting on said support between said feet and extending upwardly to said base to close the opening therein, said pads co-operating with said frame to form an air-pocket.

70

7. The combination with a typewriting machine comprising a frame having openings in its back and side walls and in its base, of means for deadening sounds produced within said frame, including members of sound-deadening material for closing said openings and co-operative with the frame to produce an air-pocket within the frame, and a sound-deadening casing enclosing said machine and forming an air-pocket around the machine.

75

8. The combination with a typewriting machine having a frame with openings in its back and side walls and in its base, of means for deadening the sounds produced within said frame, comprising sound-deadening members for closing said openings, and a sound-deadening member extending across the inside of said frame above its base.

85

9. The combination with a typewriting machine having a frame with openings in its back and side walls and in its base, of means for deadening the sounds produced within said frame, comprising sound-deadening members for closing said openings, a sound-deadening member extending across the inside of said frame above its base, and a sound-deadening casing enclosing said machine.

90

10. In a typewriting machine, the combination with an open frame inclusive of an open base, of closures of sound-deadening material for the sides and rear of said frame, a closure of sound-deadening material for the bottom of said base, type-operating key-levers extending from rear to front within said base, and a transverse layer of sound-deadening material surrounding said key-levers and co-operating with said frame and said bottom, side and rear closures to form sound-deadening air-pockets.

100

11. The combination with a typewriting machine comprising a frame having side and rear openings through which sounds produced in the operation of the machine may pass outside of said frame, of sound-deadening means for said machine including closure pads of sound-deadening material for said side and rear openings, said closure pads attached to the frame and co-operating therewith to form an air-enclosing and sound-absorbing chamber.

115

12. The combination with a typewriting machine comprising a frame having rear, bottom and side openings through which sounds produced in the operation of the machine may pass, of sound-deadening means for said machine comprising closures of sound-deadening material attached to

120

125

130

- said frame for said rear, bottom and side openings, said closures co-operative with said frame to form an interior sound-deadening pocket.
- 5 13. The combination with a typewriting machine comprising an open frame inclusive of an open base, a front key-lever guiding comb within said base and terminating at its lower end above the bottom of said base, 70
10 of sound-deadening means co-operating with said machine to form an interior air-pocket and comprising closures for the bottom, sides and rear of said frame, and a closure of sound-deadening material at said 75
15 comb and beneath the key-levers and closing the opening between said bottom closure and the line reached by the key-levers when depressed.
14. The combination with a typewriting 80
20 machine, of a base for said machine, said machine comprising a frame, a key-lever-guiding comb at the front of said frame, and spaced above the bottom of the frame, and means for supporting said frame on said 85
25 base and spacing said frame from said base, and sound-deadening means for said machine comprising a closure of sound-deadening material at the front of said frame beneath the key-levers, and extending from 90
30 said base to the line reached by said key-levers in their downward movements.
15. In combination, a typewriting machine having a front keyboard, and having a frame with openings in its back and side 95
35 walls and in its base, and having type-operating key-levers extending from rear to front of said frame and projecting forwardly at the front of the machine, and means for producing interior air-pockets 100
40 and deadening the sounds produced within said frame including closures of sound-deadening material for said openings, and also including a sheeting of sound-deadening material extending across said frame 105
45 and surmounting said key-levers in rear of said keyboard.
16. In a typewriting machine comprising a frame having rear, bottom and side openings, in combination, a key-lever-guiding 110
50 comb at the front of the machine, said comb being spaced above the bottom of said frame, thereby leaving an opening at the front of said frame, and sound-deadening means for said machine comprising a closure of sound-deadening material for each of said rear, bottom and side openings, and a closure of sound-deadening material 115
55 for said front opening below the comb.
17. In a typewriting machine, the combination with an open frame inclusive of an open base, of closures of sound-deadening material for the sides and rear of said frame, a closure of sound-deadening material for the bottom of said base, type-operating key- 120
60 levers extending from rear to front within 125
65 said base, a transverse layer of sound-deadening material surmounting said key-levers and co-operating with said bottom, side and rear closures to form sound-deadening air-pockets, and a co-operating air-pocketing element extending from side to side of the base at its front portion and having a lower portion of sound-deadening material extending from said bottom closure up to the line reached by the depressed key-levers.
18. The combination with a typewriting machine comprising a frame having a keyboard-extension, type-bars and type-bar operating mechanism mounted in said frame, said type-bar operating mechanism comprising key-levers pivoted in said frame and extending forwardly into said keyboard-extension, and bell-cranks having one arm pivoted to said key-levers at a point intermediate the length of said key-levers and the other arm pivoted to said type-bars, of means for deadening the sounds produced by the operation of the type-bar operating mechanism, said means comprising a generally horizontal layer of sound-deadening material overlying the portions of said key-levers forwardly of the points of connection to said bell-cranks.
19. The combination with a typewriting machine comprising a frame having a bottom opening, type-bars and type-bar-operating mechanism mounted in said frame, said type-bar-operating mechanism comprising forwardly and rearwardly extending key-levers pivoted in said frame, of means for deadening the sounds of said type-bar-operating mechanism, comprising a generally horizontal layer of sound-deadening material overlying said key-levers, and a sound-deadening closure for said bottom opening of the frame and co-operating with said layer and said frame to form a sound-absorbing air-pocket.
20. The combination with a typewriting machine having a frame with openings in its back and side walls and in its base and key-levers extending from front to rear of said frame, of means for deadening the sounds produced within said frame comprising sound-deadening members for closing said openings, a sound-deadening sheet secured to said frame and extending thereacross above said key-levers, and a sound-deadening casing enclosing said machine.
21. The combination with a typewriting machine having a bell-signal for signaling the approach of the end of a line, of a sound-deadening casing for the machine, and means for mounting said bell-signal outside of said casing, said means comprising a support fixed at one end to said machine and extending outwardly through said casing, said bell-signal being fixed to said support at the other end thereof outside of said casing.

22. The combination with a typewriting machine having a bell-signal for signaling the approach of the end of a line, and means for ringing said bell-signal comprising a rearwardly-extending hammer, of a sound-deadening casing for the machine, and means for mounting said bell-signal outside of said casing, said last-named means comprising a support fixed at one end to said machine and extending outwardly through said casing, said bell-signal being fixed to said support at the other end thereof outside of said casing, said hammer having an outwardly-extending rearward 10 end to co-operate with said bell-signal.

23. The combination with a typewriting machine having a bell-signal for signaling the approach of the end of a line, and means for ringing said bell-signal comprising a rearwardly-extending hammer, of a sound-deadening casing for the machine, and means for mounting said bell-signal outside of said casing, said last-named means comprising a bracket fixed on said machine, and a laterally-extending support fixed at one end in said bracket and extending through said casing, said bell-signal being fixed to said support at the other end thereof outside of said casing, said hammer having a laterally-extending rearward end 20 to co-operate with said bell-signal.

24. The combination with a typewriting machine comprising a frame having openings in its back and side walls and in its base, key-levers extending from front to rear of said frame, type-bars and type-bar-actuating members connected with said key-levers, of means for deadening the sounds produced within said frame, comprising sound-deadening members for closing said openings, a sound-deadening sheet secured to said frame and overlying said key-levers at the front of said type-bar-actuating members, and a sound-deadening sheet secured 30 to said frame and overlying said key-levers to the rear of said type-bar-actuating members.

25. The combination with a typewriting machine having a bell, of a sound-deadening casing having an opening containing said bell, to permit said bell to project therefrom and to be heard outside of said casing, said bell serving to practically close said opening in said casing, and striking means 40 extending from said machine to said bell.

26. The combination with a typewriting machine comprising a carriage and a platen on said carriage, of a sound-deadening casing for the machine, said casing having a slot therein, and means connected to rotate said platen back and forth, said means being disposed perpendicularly to the travel 50 of said carriage and extending through said slot so that it may travel with the carriage and be operated from the outside of

said casing, said rotating means having a flexible connection with said platen to permit case-shifting movements of the platen.

27. In a typewriting machine, the combination of a carriage, a platen, a platen-frame to support said platen, said platen-frame being mounted for case-shifting movements in said carriage, a finger-piece rotatably supported on said carriage, and means connecting said finger-piece with said platen so that the latter may be rotated by said finger-piece, the connection being yieldable to permit case-shifting movements of the platen-frame with said platen. 70

28. In a typewriting machine, the combination of a carriage, a platen, a platen-frame to support said platen, said platen-frame being mounted for case-shifting movements in said carriage, a platen-axle, a bracket on the platen-frame to support the axle near one end thereof, a gear on said platen-axle, driving means comprising a shaft disposed perpendicularly to the platen-axle, a gear on said shaft meshing with the gear on the platen-axle, a bracket to support one end of said shaft, said bracket being mounted on the platen-axle and swingable about the latter, a rotatable finger-piece, a bracket on said carriage to support said finger-piece, and a universal joint connecting said finger-piece with said shaft to permit the platen-frame to be shifted with said platen relatively to the finger-piece on said carriage. 80

29. In a typewriting machine, the combination of a carriage, a platen, a platen-frame to support said platen, said platen-frame being mounted for case-shifting movements in said carriage, a platen-axle, a bracket on the platen-frame to support the axle near one end thereof, a gear on said platen-axle, driving means comprising a shaft disposed perpendicularly to the platen-axle, a gear on said shaft meshing with the gear on the platen-axle, a bracket to support one end of said shaft, said bracket being mounted on the platen-axle and swingable about the latter, a rotatable finger-piece connected with said shaft to rotate said platen, the forward end of said shaft being supported by said carriage, and means to permit the rear end of said shaft to be swung up and down with the platen during case-shifting movements of the latter. 100

30. In a typewriting machine comprising printing devices including key-levers extending from the front to the back of the machine and pivoted at their rear ends on the frame of the machine, said frame comprising two sides joined at the rear by a cross-bar, four feet to support said machine, and a sound-deadening casing around said machine, the combination of means disposed above said key-levers to muffle the sound produced by the printing operations before 110

said sound emanates from the casing below said key-levers, and means disposed under the sides and the rear cross-bar of the frame between the feet of the machine to assist in 5 muffling the sound.

31. The combination with a typewriting machine comprising a platen-frame, a shaft journaled in said frame, a platen fixed to said shaft, a bell and means for tapping said 10 bell upon the approach of the end of a line, of a sound-deadening casing for the machine, said casing having an opening to permit the bell to project therethrough to enable the bell to be heard outside of the 15 casing, means connected to said platen and projecting forwardly through said casing whereby said platen may be rotated from the front of the casing, said means comprising an operating shaft having a forward 20 part and a rearward part, a universal joint connecting said parts, and a gear fixed to the rearward end of said rearward part, a gear fixed to one end of the platen-shaft and meshing with said first gear, and a bracket 25 fixed to said platen-frame and supporting said platen-shaft and the rearward part of said operating shaft, to hold said gears in meshing engagement in the lowered and shifted positions of said platen, said uni- 30 versal joint permitting said rearward part of the operating shaft to move relatively to said forward part when the platen is shifted. 32. In a typewriting machine, the combination of a carriage-frame, a platen- 35 frame shiftable on said carriage-frame, a platen rotatably supported on said platen-frame and shiftable with said platen-frame, a finger-wheel supported on said carriage-frame and connected with the platen to 40 rotate the latter back and forth, and means to permit said platen to be shifted relatively

to said finger-wheel without breaking the connection with said platen.

33. The combination of a sound-deadening casing having an opening therein, of a 45 bell substantially closing said opening to co-operate with the casing for sound-deadening purposes.

34. The combination with a typewriting machine having a frame with rear and side 50 openings, of silencing means to intercept and absorb sound waves and including a sound-absorbing rear pad secured to the typewriting machine and closing its rear opening, and also including pads of sound- 55 deadening material secured in and closing the side openings of the machine, said closure pads of such a character that there is substantially no reflection of sound waves therefrom, said closure pads cooperatively 60 forming a sound-deadening air-chamber.

35. The combination with a typewriting machine having a frame with rear, side and bottom openings, of silencing means to intercept and absorb sound waves and including a sound-absorbing pad mounted upon 65 said frame and closing the opening in the back of the typewriting machine, and also including sound-absorbing pads mounted upon said frame and forming closures for 70 the sides of the machine, and a sound-absorbing pad forming a closure for the bottom of said frame, all of said closures of such a character that there is substantially 75 no reflection of sound waves therefrom, said closures co-operatively forming a sound-deadening air-pocket.

BURNHAM C. STICKNEY.
